(57) CLAIM

I claim the ornamental design for money clip, as shown.

DESCRIPTION

FIG. 1 is a perspective view with the present invention in its folded state;

FIG. 2 is a perspective view thereof showing the design in its opened state;

FIG. 3 is a front elevational view of the present invention in its folded state with the rear elevational view being a mirror image of the front elevational view;

FIG. 4 is a left side elevational view, thereof;

FIG. 5 is a right side elevational view, thereof;

FIG. 6 is a top plan view, thereof; and,

FIG. 7 is a bottom plan view.
